UNITED STATES PATENT OFFICE

DOMINICK BEVILACQUA, OF LONG ISLAND CITY, NEW YORK, ASSIGNOR TO I. MILLER & SONS, INCORPORATED, A CORPORATION OF NEW YORK

JACK STAND

Application filed March 18, 1931. Serial No. 523,409.

This invention relates to the shoe machine art and deals more specifically with a jack stand.

In certain operations during the processes of shoe manufacture, and particularly in the manufacture of turn shoes, the shoe having a last therein is placed upon a jack to hold the same firmly while the shoemaker works on the shoe.

10 It is therefore an object of this invention to provide a jack stand upon which a jack may be removably mounted, which stand is simple and cheap to construct, while at the same time giving a rigid support for the jack.

15 Further, it is an object of this invention to provide a jack stand which gives the greatest freedom to the shoemaker in operating upon the shoe supported thereon.

And finally, it is an object of this invention 20 generally to improve the jack stand art and to render the same more durable and efficient.

These and other objects of the invention will be readily apparent to those skilled in the art from the following description taken 25 in connection with the accompanying drawings, in which:

Fig. 1 is a side elevation of a stand constructed in accordance with the present invention;

20 Fig. 2 is a perspective view of the device shown in Fig. 1, the jack being removed; and

Fig. 3 is a perspective view of a modification.

Referring in detail to Figs. 1 and 2, the 35 stand 10 is seen to comprise a base 11 having holes 12 therein, whereby the base may be screwed or bolted down. The base also has a pair of rearwardly extending members 13 and a cross support 15 in which is pivoted at 16 the foot treadle 17 having the arm 18 and foot portion 19. A standard or frame 20 having the supports 21 and 22 is fixed to the base, the support 21 being approximately two-thirds of the length of the support 22 40 and the two being joined by the angularly disposed cross strut 23 as shown. A bracket plate 25 is bolted to the support 22. The plate 25 is provided with holes 26 through which the jack 30 is adapted to be bolted. 45

50 It will be understood that the several holes

provided in the bracket may be positioned as desired, whereby the jack may be fixed on the stand in several different positions and adjustments as desired to suit the needs of the shoemaker. A table 31 is fixed to the support 22 and has at its rear end a plate 32 which may be bolted to the shoemaker's bench (not shown). The table 31 is L-shape and is constructed preferably of the same material as the supports 21 and 22. It will be noted that the freedom permitted the workman in operating upon a shoe held on this device is very great, by virtue of the space provided by the foreshortening of the support 21, as well as by virtue of the fact that the table is L-shaped and thus provides for considerable space around the jack. A coiled spring 35 is connected between the treadle arm 18 and the table 31 for the purpose of holding the treadle normally in its uppermost position. An important feature of the spring 35 is that it is joined to the right side of the table 31, so that it is disposed at an angle with respect to the horizontal plane and thereby not only urges the treadle 17 upwardly but also to the right. A plate 40 having ratchet teeth 41 therein is mounted between the supports 21 and 22. The plate 40 has a slot 43 through which the treadle arm 18 extends, and the slot is of sufficient width so that the arm 18 may be moved upwardly under tension of the spring 35 and downwardly under foot pressure, without engaging the ratchet teeth. By virtue of the fact that the spring 35 is angularly disposed, as described above, the arm 18 normally is drawn to the right by a component of the force of the spring which depends upon the cosine of the angle of the spring 35 with respect to the horizontal. When the operator wishes to depress the treadle and leave it in such a position, he bears down on the foot portion 19 and when the position to be held is reached, he moves the treadle to the left, thus causing the arm 18 to engage a ratchet tooth. In order to hold the shoe firmly on the jack, a heavy leather saddle 45 is provided and the rope 46 is joined to opposite ends thereof. The rope 46 passes through an eye 47 which is joined to a coiled spring 48 which is in 103

turn pivotally connected to a link 49. The link 49 is pivotally connected to the arm 18 in any suitable manner. It will be seen that by means of the treadle 17 and the saddle 45 5 the shoe may be held firmly on the jack. The details of the structure of the jack have been omitted because any jack of the prior art is suitable for use in this invention, it being merely necessary that the same be provided 10 with bolts and nuts for attachment to the bracket plate 25.

The parts of the jack stand constructed in accordance with this invention are preferably made of fabricated steel welded, riveted, or bolted together. However, the stand 15 may be cast of iron or steel.

Referring now to Fig. 3, this modification of the invention differs from that of Figs. 1 and 2 only in that the support 121 is of full 20 length and the table 131 is attached to two extensions 121a which extend at right angles to the supports 121 and 122. The jack 30 is fixed to the table by bolts (not shown) or any other suitable means. Except for these differences the description of Figs. 1 and 2 applies also to Fig. 3.

Having thus described my invention, I claim:

1. A jack stand comprising a base member, a frame comprising two vertical supports, one of which is longer than the other, an L-shaped table joined to said longer support, and means to support a jack on said frame.

25 2. A jack stand comprising a base member, two vertical supports, one of which is shorter than the other, an L-shaped table joined to said other support, means to support a jack, a pivotally mounted foot treadle, means to engage the work on said jack, 40 means connecting said last mentioned means and said treadle, and means for locking said treadle in place.

3. A jack stand comprising a base member, two vertical supports, one of which is shorter than the other, an L-shaped table joined to said other support, means to support a jack, a pivotally mounted foot treadle, spring means normally holding said treadle 45 upward, means to engage the work on said jack, means connecting said last mentioned means and said treadle, and means for locking said treadle in place.

4. A jack stand comprising a base member, two vertical supports, one of which is shorter than the other, an L-shaped table joined to said other support, means to support a jack, a pivotally mounted foot treadle, spring means normally urging said treadle 50 upward and to one side, means to engage the work on said jack, means connecting said last mentioned means and said treadle, and means for locking said treadle in place.

5. A jack stand comprising a base member, two vertical supports, one of which is

shorter than the other, an L-shaped table joined to said other support, means to support a jack, a pivotally mounted foot treadle, means to engage the work on said jack, 70 spring means connecting said last mentioned means and said treadle, and means for locking said treadle in place.

6. A jack stand comprising a base member, two vertical supports, one of which is shorter than the other, an L-shaped table joined 75 to said other support, means to support a jack, a pivotally mounted foot treadle, spring means normally holding said treadle upward, means to engage the work on said jack, spring means connecting said last mentioned means and said treadle, and means for locking said treadle in place.

7. A jack stand comprising a base member, two vertical supports, one of which is shorter than the other, an L-shaped table joined 80 to said other support, means to support a jack, a pivotally mounted foot treadle, spring means normally urging said treadle upward and to one side, means to engage the work on said jack, 85 spring means connecting said last mentioned means and said treadle, and means for locking said treadle in place.
